(57) **CLAIM**

The ornamental design for a band for hose clamp, as shown and described.

DESCRIPTION

FIG. 1 is a perspective view of a band for hose clamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged partial view of the front elevational view thereof; and,

FIG. 9 is an enlarged cross-sectional view thereof, taken along line 9-9 of FIG. 8.

The broken lines in the drawings illustrate portions of the band for hose clamp and form no part of the claimed design. All portions of the band for hose clamp located between the break lines form no part of the claimed design.
